Primary Examiner — Cathy Anne MacCormac(57) **CLAIM**

The ornamental design for a pet kennel, as shown and described.

DESCRIPTION

FIG. 1 is a top right-side perspective view of a pet kennel showing my new design;

FIG. 2 is a top left-side perspective view thereof;

FIG. 3 is a bottom left-side perspective view thereof;

FIG. 4 is a front view thereof;

FIG. 5 is a back view thereof;

FIG. 6 is a top view thereof;

FIG. 7 is a bottom view thereof;

FIG. 8 is a left-side view thereof; and,

FIG. 9 is a right-side view thereof.

The broken lines depict environmental subject matter and form no part of the claimed design.
